UNITED STATES PATENT OFFICE

LEE SING FOO, OF MANCHESTER, NEW HAMPSHIRE

MAGAZINE FUSE

Application filed August 5, 1927. Serial No. 210,928.

This invention relates to a magazine fuse, the object being to provide a device which will feed a plurality of cartridge fuses in position to maintain a distribution circuit indefinitely. Devices of this kind have heretofore been provided but are commonly made of flexible fuse wires fed from a reel and which on blowing of the fuse can be unreeled a sufficient distance to restore the integrity of the distribution circuit. My invention, however, differs from devices of this kind in providing a magazine fuse holder attachable to a fixture mounted on the wall of the house or station and which, on blowing the fuse, will automatically permit ejection of the blown fuse and its replacement by another from the magazine, this operation being continuous for a plurality of overloads of the consumption circuit and may then be rendered of further use by a new supply of cartridge fuses. The fuse casing is formed of an insulating holder in which a plurality of fuses may be consecutively lowered into engagement with a circuit terminal by which any fuse lowered by a compression spring may be brought into circuit-closing position automatically when the blown fuse is ejected. The magazine, the walls of which are of suitable insulating material, as indurated fiber, carries imbedded wires by which the circuit is automatically completed, when a fresh fuse is pushed by the spring into engagement with the circuit closing terminal.

The invention therefore, in its broader phase, involves a magazine fuse containing a plurality of cartridge fuses having a compression spring driving them toward the open end, and circuit closing detents at the open end by which the blown fuse may be discharged automatically and a fresh fuse installed in its place. It comprises other features, the novelty of which will be more fully hereinafter described and will be definitely indicated in the appended claims.

45 In the drawings illustrating the invention:

Figure 1 is a vertical sectional view taken through the device forming the subject matter of the present invention, and illustrating parts in elevation.

50 Figure 2 is a partial vertical sectional view

taken through the fuse magazine or holder, with parts in elevation and in dotted lines.

Figure 3 is a horizontal sectional view taken through the fuse magazine or holder.

Figure 4 is a sectional view taken through 55 the fuse magazine or holder adjacent the top thereof with the cover for said holder removed and showing a fuse and other parts in elevation.

Figure 5 is a horizontal sectional view taken 60 through the support strip and showing the upper socket or bracket terminal in section.

Figure 6 is a detail view of the upper hook.

Figure 7 is a perspective view of an angle 65 bracket which forms a part of the invention, for securing the cover of the fuse magazine or holder in closed position.

Figure 8 is a similar view of the upper bracket terminal.

Figure 9 is a similar view of one contact 70 member for the fuses.

Figure 10 is a similar view of the other contact member.

Referring to the drawings in detail, the reference numeral 1 indicates a supporting 75 strip of fiber slate or other suitable insulating material adapted to be secured in any well known manner to the wall of a building or the like, and secured to the strip by set screws is a bracket terminal 2 which includes a folded clip 3 for the purpose of accommodating one end of a conductor 4, and the bracket terminal also includes a substantially rectangular shape socket member including side walls 5 and 5^a and a front wall slotted longitudinally to provide spaced portions 6 and 6^a as clearly shown in Figure 8 of the drawings. The socket is adapted to receive the finger of a U-shape support or hook 7 which is secured to one of the end walls of a fuse magazine or holder 8 in a manner as clearly shown in Figure 1. The hook 7 is secured to the end wall by set screws, and a bracket terminal 2^a similar to the bracket terminal 2 is mounted adjacent the bottom of the wall to cooperate 85 with a hook 7^a similar to the hook 7, the hooks 7 and 7^a being received in the rectangular portions of the bracket terminals.

The fuse magazine or holder is rectangular 90 in shape as best shown in Figure 3, and is 100

formed from insulating material. One side wall of the holder is provided with a vertically arranged groove or recess of arch cross sectional shape and this recess is indicated by the reference numeral 9. Formed in the opposite side wall is a vertically arranged recess 10, rectangular in cross section, the recess 9 forming a vertical guide for the rounded boss on one of the ends of the cartridge fuses as shown, and the groove 10 forms a guide for the posts 12 of the fuses.

The fuse holder is provided with a cover 13 which when in closed position applies pressure to the fuses 14 through the medium of a spring means which will be presently described, and the cover has depending therefrom adjacent the ends thereof flanges 15 and 15^a. Secured to the underside of the cover through the medium of rivets or the like is one end portion of a looped spring 16 which has secured to its opposite or lower end, a plate 17 having flanges curved to follow the curvature of the fuse 14 as best shown in Figure 2 of the drawings.

Secured to the end wall which carries the hooks 7 and 7^a is a spring contact member 18 that is arranged adjacent the bottom of the last mentioned end wall and includes a spring finger disposed in the path of the post 12 of the fuses as clearly shown in Figure 1.

In order to retain the cover in closed position, the flange 15^a is provided with an opening that registers with a similar opening in the other wall of the fuse holder, and these registering openings receive a pin 19. Co-operating with the pin 19 is an angle plate 18' that includes a short arm 19' adapted to be received in a slot formed in the flange 15.

The structure of the fuses is clearly shown in Figure 1, and each of the fuses not only include a post 12, but likewise include a fusible neck 20 of a cross section according to the required amperage. Formed with each of the ends of the neck are conical shape portions 21 and 21^a, the portion 21 has formed therewith a guide 22 from which extends the post 12, and the guide is of a size to snugly fit within the easing of the fuse but is mounted for slidable movement therein. Disposed about the portion 23 of the post 12 is a coil spring 24 that has one of its end convolutions engaging the guide 22, while its opposite end convolution engages a plug 26 which closes one of the ends of the fuse and extending from diametrically opposite sides of the plug 26 as well as a portion of the fuse having formed therewith the portion 21^a and the boss 11 are pins 25 which are received in the casing as shown. By this construction, it will be obvious that when the neck 20 becomes broken, the coil spring 24 will urge the post 12 out of engagement with respect to the finger of the spring contact 18. The casings of the fuses may be formed from fiber or similar insulating material. The spring contact 18

is secured to the fuse holder by set screws which likewise secure the hooks 7^a thereto as clearly shown in Figure 1.

It will be apparent therefore that when the cover is removed the cartridges may be dropped into the casing and when the cover is applied the pressure of the spring 16 will force the bottom fuse into engagement with the spring 18 and the copper or brass terminal 27 which is secured to the front wall of the magazine by one or more set screws 28. In the walls of the magazine are mounted a metallic strip 29 which may be done in process of formation or mounted on the outside thereof but in any event terminates in metallic continuity with the brass or copper terminal 27. The metallic strip 29 is in metallic continuity or engagement with a transverse metallic strip 29^a which terminates in contact with the upper hook 7, whereby there is metallic continuity between the terminal 2, the hook 7, the wires 29, 29^a to the bottom terminal 27. Consequently, when the cartridges are stacked in the fuse magazine and the cover applied, the bottom cartridge is automatically forced into engagement with the terminals 18 and 27 so that the fuse is placed in circuit with one conductor 4 and the corresponding opposite conductor 4^a of the circuit. On overloading of the circuit the narrow neck 20 of the fuse gives away by melting and the spring 24 causes the terminal 23 to leave the spring 18 and automatically drop away from the magazine, whereupon the pressure of the spring 16 drives a new cartridge fuse into its seat between the spring 18 and the terminal 27, thereby renewing the integrity of the circuit. Similarly this operation will continue as long as spare cartridge fuses are supplied to the magazine.

While I have shown a certain specific form of construction, it is obvious that modifications of the holder and its support may be made without departing from its scope and is only limited by the terms of the appended claims.

Having thus described my invention, what I claim as new and desire to secure by Letters Patent is:

1. In a fuse magazine holder, a strip of insulating material, bracket terminals including clips for receiving conductors and being secured to the strip, an open bottom holder, cartridge fuses adapted to be received in said holder, hooks secured to said holder and detachably received by said bracket terminals, a cover for said holder, means for securing said cover in operative position, a spring having one end secured to said cover, an arched bottom piece secured to the opposite end of said spring and engageable with an adjacent cartridge fuse, a spring contact having connection with one hook and secured in said casing in the path of posts of the cartridge fuses, a terminal secured in the holder in opposed

direction with respect to the spring contact and arranged in the path of the cartridge fuses, and metallic means completing a circuit between the other hook and the said terminal.

2. A magazine fuse device comprising a strip of insulating material, means secured to said strip and receiving conductors, a cartridge fuse holder, means secured to said holder and received by the first mentioned means whereby the holder is supported with respect to the strip, cartridge fuses adapted to be received in said holder said holder having recessed sides for guiding the cartridge fuses for movement therein, a cover for said holder, a coil spring secured to said cover, an arched bottom piece secured to said coil spring for engagement with an adjacent cartridge fuse for urging said cartridge fuses through said holder, a spring contact secured in said holder in the path of cartridge fuse posts, said spring contact being electrically connected with one conductor through the medium of a portion of the holder supporting means, a terminal arranged in opposed relation with respect to the spring contact, for engagement with the cartridge fuses, metallic means embedded in said holder for electrically connecting the terminal with the other conductor through the medium of the remaining portion of the holder supporting means, said holder having an open bottom, and resilient means included in said cartridge fuses for the purpose specified.

3. A magazine fuse device comprising a strip of insulating material, conductor receiving means secured to said strip a cartridge fuse holder, means secured to said cartridge fuse holder and supported by the conductor receiving means for securing said holder with respect to said strip, cartridge fuses including casings and adapted to be mounted in said holder, enlarged terminals included in each cartridge fuse, a metallic post for each cartridge fuse, a plug having a post passing therethrough, a coil spring surrounding the post and engaging the plug and one of said terminals, contact means arranged in said holder and being bridged by one of the cartridge fuses, one of said contact means being in electrical connection with one conductor, metallic means electrically connecting the other contact means with the other conductor, and a coil spring for urging the fuses in contact with said contact means.

In testimony whereof I affix my signature.
LEE SING FOO.
